[57] CLAIM

The ornamental design for a bicycle headset cap, as shown
and described.

DESCRIPTION

FIG. 1 is a perspective view of a bicycle headset cap
showing my new design, the broken line portions of the
bicycle are shown for illustrative purposes only and form no
part of the claimed design;FIG. 2 is a top view of the bicycle headset cap of FIG. 1,
with advertising indicated in broken lines.FIG. 3 is a second top view of the bicycle headset cap of
FIG. 1 with the location of artwork, design or logo indicated
by broken lines of those words.FIG. 4 is a bottom view of the bicycle headset cap of FIGS.
1, 2 and 3; and,FIG. 5 is a side view of the bicycle headset cap of FIGS. 1,
2, 3 and 4. Since the bicycle headset cap is symmetrical, all
side views would appear the same as FIG. 5.
